PORTABLE TROUBLE LIGHT

Lawrence L. Flaugh, Pewaukee, and Thomas G. Bur,
Elm Grove, Wis., assignors to Applied Power Industries,
Inc., a corporation of Wisconsin

Filed Oct. 11, 1961, Ser. No. 67,042

Term of patent 7 years

(Cl. D48—20)

fig. 1

fig. 2

fig. 4

fig. 3

FIGURE 1 is a perspective view of a portable trouble light embodying our new design;

FIGURE 2 is a side elevation thereof, with the cord and plug omitted for convenience of illustration;

FIGURE 3 is a top plan view thereof; and

FIGURE 4 is a bottom plan view thereof.

The lighting tube is shown in dotted lines for illustrative purposes only, and the cord is shown broken away in part to indicate indeterminant length.

We claim:

The ornamental design for a portable trouble light, substantially as shown and described.
